UNITED STATES PATENT OFFICE.

OTTO SPAETH, OF CHICAGO, ILLINOIS.

LOCOMOTIVE ASH-PIT.

949,162.

Specification of Letters Patent. Patented Feb. 15, 1910.

Application filed April 28, 1909. Serial No. 492,759.

To all whom it may concern:

Be it known that I, OTTO SPAETH, a citizen of the United States, residing at Chicago, county of Cook, and State of Illinois, 5 have invented certain new and useful Improvements in Locomotive Ash-Pits, of which the following is a specification.

My invention relates to improvements in means for inducing an air draft through 10 locomotive ash pits, whereby forward movement of the locomotive induces said draft.

The object of my invention is to provide improved means for this purpose, whereby the maximum amount of draft is obtained 15 with the least expenditure of power, and my invention consists in the combination and arrangement of the parts hereinafter described and claimed.

In the drawings Figure 1, is a section 20 through a fire box and ash pit equipped with my invention, and Fig. 2, a bottom plan view of the fire box and ash pit.

Referring to the drawings, 1 indicates the ash pit, 2 the grate, 3 the fire box, 4 the 25 engine cab and 5 the boiler. These parts are all old and well known, and may be of any of the usual or desired constructions. At the rear, ash pit 1, is provided with a curved draft tube 6 communicating with the 30 rear of the ash pit and terminating with a forwardly projecting mouth 7, located under the rear of the ash pit and being flaring in form. At either side the ash pit is provided with diverging and forwardly projecting draft tubes 8, communicating with the 35 ash pit at about its middle. By this construction it will be seen that as the locomotive moves forwardly, as indicated by the arrow in Fig. 1, air will be forced into 40 tubes 6 and 8, passing thence into the ash pit 1, and up through grate 2, into the fire box 3, whence it passes out through the smoke stack in the usual manner.

Owing to the fact that the mouth of tube 45 6 is below its discharge into the ash pit, the heat in the ash pit, which naturally tends to make the air rise, will assist the pressure induced by the forward movement of the locomotive to cause the air to pass upwardly

through the grate. The tubes 8 being horizontal, the heat will not tend to resist the entry of air. The draft entering the ash pit through the tube 6 is met by the draft entering through side tubes 8, thus being broken up and distributed uniformly under the 50 grate. This insures a uniform draft through the grate and consequently a uniform fire thereon. In this manner sufficient draft will be induced through the grate 2, to dispense with the necessity of using exhaust 55 steam from the engine for this purpose, leaving the exhaust steam available for other purposes.

While I have illustrated and described the preferred construction for carrying my 60 invention into effect, this is capable of some modification without departing from the spirit of the invention. I, therefore, do not wish to be limited to the exact construction set forth, but wish to avail myself of such 65 changes and modifications as come within the scope of the appended claims.

Having described my invention what I 70 claim as new and desire to secure by Letters Patent is:

1. The combination with the ash pit of a locomotive, of a draft tube extending from the rear thereof and having a forwardly projecting mouth located under the ash pit; and supplemental side draft tubes projecting 75 forwardly from each side of the ash pit, substantially as described.

2. The combination with the ash pit of a locomotive, of a draft tube extending from the upper rear portion thereof and having a forwardly projecting mouth located under the rear of the ash pit, the mouth of said tube being flaring; and supplemental side draft tubes diverging and flaring forwardly from each side of the 80 ash pit, substantially as described.

In testimony wherof I have signed my name to this specification in the presence of two subscribing witnesses.

OTTO SPAETH.
